Des. 218,329
Patented Aug. 11, 1970

218,329

BAR SOAP CONTAINER

Ronald L. Weaver, Rte. 1, Box 130,
Lebanon, Oreg. 97355

Filed Nov. 25, 1968, Ser. No. 15,186

Term of patent 14 years

Int. Cl. D6—01

U.S. Cl. D33—24

Fig. 1

Fig. 2

Fig. 3

Fig. 4

FIG. 1 is a perspective view of a combination soap container and soap dish, showing my new design;

FIG. 2 is an elevational view taken from one end thereof, the opposite end being a mirror image of the end shown;

FIG. 3 is a rear elevational view thereof; and

FIG. 4 is a bottom plan view thereof.

I claim:

The ornamental design for a bar soap container, substantially as shown and described.
